UNITED STATES PATENT OFFICE

2,062,932

AUTOMOBILE SIGNAL LIGHT

Harold Redman, Pontiac, Mich.

Application June 10, 1936, Serial No. 84,574

1 Claim. (Cl. 177—329)

This invention relates to an automobile signal light.

It aims to provide a novel construction adapted for mounting or connection to a lamp bracket or other part at the rear of an automobile and to be operated by switch means on the instrument board or the like, to indicate by a novel illuminated means, the direction of an intended turn.

It is also aimed to provide novel means at the switch or switches employed, to positively indicate which switch is associated with the mechanism for the particular turn.

The more specific objects and advantages will become apparent from a consideration of the description following taken in connection with accompanying drawing illustrating an operative embodiment.

In said drawing:—

Figure 1 is a view in elevation and partly in electrical diagram;

Figure 2 is a horizontal sectional view taken on the line 2—2 of Figure 1, and

Figure 3 is a cross-sectional view taken on the line 3—3 of Figure 1.

Referring specifically to the drawing wherein like reference characters designate like or similar parts, a signal box or casing is provided at 10 and subdivided by a partition as at 11 providing compartments at 12 and 13. The front wall 14 of the box or casing 10 is cut away as at 15 providing an arrow shaped opening for signaling purposes and is cut away as at 16, in the shape of an arrow also for signaling purposes, the cut away portions 15 and 16 respectively being opposite the compartments 12 and 13. A glass panel 17 is fastened in the rear of the wall 14 and is preferably red in color and has a letter L in black delineated thereon at the opening 15 and the letter R in black delineated thereon opposite the opening 16, to respectively indicate left and right hand turns.

The box or casing 10 may be mounted in any suitable manner at the rear of an automobile or other vehicle as by means of a bracket 19 and accessory parts, engaging a lamp bracket on the automobile or any other suitable part.

In the chambers 12 and 13, lamps 20 and 21 are preferably secured in suitable sockets 22 and 23, respectively.

The source of electric energy for lighting the lamps 20 and 21 may be the starting and lighting battery for the automobile as suggested at 24. One terminal thereof is grounded as at 25 and one terminal of each of the lamps is also 5 grounded as at 26. From the other terminal of the battery 24, a conductor 27 leads, branching into conventional switches at 28 and 29 from which conductors 30 and 31 lead to the lamp sockets 22 and 23, respectively.

The caps of the switches 28 and 29 are shown and are preferably white in color, the switches being of any conventional form.

To positively indicate which switch should be operated to indicate a right or left hand turn, 15 triangular or arrow shaped plates 32 and 33 are connected thereto, being colored red or otherwise as preferred and having the letters L and R delineated thereon in black or otherwise to contrast with the color thereof.

It will be seen that when a left hand turn is to be made, the plate 32 is operated so that the circuit through the lamp 20 will be closed to indicate that a left hand turn is contemplated. On the other hand, when a right hand turn is 25 to be made, the plate 33 is operated to control the switch 29 and energize the lamp 21 to illuminate the right hand signal.

As shown in the drawing casing 10 has the upper and lower walls 34 and 35, respectively, also 30 the partition 11 and end walls 36 secured to the rear wall 37. The bottom wall is provided with an integral U-shaped recess 38 to receive the lower edge of the front wall 14, that is removable for replacing the lamps 20 and 21, and is held in 35 place by means of bolts and nuts 39 secured thereto and to the rear wall 37.

Changes may be made within the spirit and scope of the invention.

I claim as my invention:—

A vehicle signal of the class described comprising a casing having a flange projecting beyond one face thereof, a signal wall resting on said flange and disposed against said face, said signal wall having integral inner and outer sheets, a 45 diaphanous panel between said sheets, and bolt means fastening the signal wall to the casing and urging said sheets together to hold the panel against rattling.

HAROLD REDMAN.
